UNITED STATES PATENT OFFICE.

LOUIS N. EMMETS, OF BROOKLYN, NEW YORK, ASSIGNOR TO KIDDIES METAL TOYS, INC., A CORPORATION OF NEW YORK.

DESIGN FOR A SAND PAIL.

Application filed November 28, 1923. Serial No. 7,900. Term of patent 7 years.

To all whom it may concern:

Be it known that I, LOUIS N. EMMETS, a citizen of the United States, residing at 23 34th Street, in the borough of Brooklyn, county of Kings, and State of New York, have invented a new, original, and ornamental Design for Sand Pails, of which the following is a specification, reference being had to the accompanying drawing, forming part thereof.

The figure is a top perspective view of a sand pail, showing my new design.

I claim:

The ornamental design for a sand pail, as shown.

LOUIS N. EMMETS.
